ANTISKID CHAIN

Filed Nov. 9, 1931

INVENTOR
Giles A. Beckwith,
By Archworth Martin,
Attorney.

UNITED STATES PATENT OFFICE

GILES A. BECKWITH, OF WATERFORD, CONNECTICUT

ANTISKID CHAIN

Application filed November 9, 1931. Serial No. 573,800.

My invention relates to anti-skid chains, such as are employed on automobile tires, etc., and particularly to those portions of the chains which engage the roadway.

5 One object of my invention is to provide a chain that is of longer life than various types of chains heretofore employed.

Another object of my invention is to provide a chain which possesses superior anti-10 skid properties.

Still another object of my invention is to provide an anti-skid chain possessing the advantages above-named, and which is nevertheless of comparatively simple construction.

15 Some of the forms which my invention may take are shown in the accompanying drawing, wherein Figure 1 is a plan view showing the road-engaging surface of a cross chain; Fig. 2 is a side elevational view thereof, and Fig. 3 is a view similar to Fig. 1, but showing a modified form of chain link.

Referring first to Figs. 1 and 2, portions of the usual side chains or tension members are indicated by the numerals 4. The side 25 chains 4 are connected at intervals by cross chains that extend across the tread of the wheel. Each cross chain includes tread links 5 which are shown as of approximately circular form, and each of which is twisted for a 30 distance of approximately 180° to permit the links to lie substantially in a common plane, in a manner well-known in the twisted link art.

The bends formed in the links at points 35 where they cross one another extend outwardly from the mid plane of the links at diagonally opposite points, as indicated at 6 and 7, for example. Ordinarily, the links tend to wear through rapidly at these points, and 40 furthermore there is tendency for these curved protrusions to slip on the roadway. Metal bars 8 are welded to the links at diagonally-opposite low points thereof, while the bars 9 extend diagonally of the links and are 45 welded thereto at points adjacent to the raised or protruding portions 6 and 7 of the links, the bars 8 and 9 preferably being of polygonal form in cross section.

The bars or calks 9 serve not only to more 50 effectively resist skidding than links which

are not provided with calks, but also increase the life of the links, because the links will not begin to wear until the calks 9 are worn entirely through or nearly through.

While the major portion of the calks 8 are 55 not subjected to wear until the bars 9 have been worn nearly through, the ends thereof, by reason of the rocking tendency of the chain under tractive or braking forces of the wheel will bite into the roadway and resist 60 slipping of the wheels. When the bars 9 have been more worn through, the bars 8 will not only relieve the links of considerable wear, thus further lengthening the life thereof, but 65 they will, by reason of their diagonal positions, resist skidding, and will increase the tractive quality of the chain.

Referring now to Fig. 3, I show a structure similar to that of Fig. 1, but wherein the tread links 10 have loop-like extensions 11, the links or their extensions, or both, being twisted to permit the links to lie in substantially a common plane. In this case, bars or calks 12 and 13 are provided that 70 correspond to the bars 8 and 9, respectively, 75 of Fig. 1.

These bars serve to protect the links against 75 excessively rapid wear, and also assist the links in resisting skidding.

In the structures of both Figs. 1 and 3, 80 the tread links are somewhat larger than links commonly employed on tire chains, with the result that there is not excessive 85 rolling of the links under tractive forces of the wheels, and the openings through the links between the bar-like calks are not so small that they become readily clogged with snow.

If desired, the bars may be welded together 90 at the points where they cross one another.

I claim as my invention:—

1. An anti-skid cross chain comprising 95 links of approximately circular form but having loop-like extensions, the extensions of adjacent links being directly connected and the links being twisted at said extensions to cause the links to lie in substantially a common plane, a bar-like calk secured at its ends to each of said links at the raised portions of the links which result from the twisting 100

thereof, and a bar-like calk secured at its ends to each of said links at depressed portions of the links.

2. An anti-skid cross chain comprising 5 links of approximately circular form but having loop-like extensions, the extensions of adjacent links being directly connected and the links being twisted at said extensions to cause the links to lie in substantially a common plane, a bar-like calk secured at its ends to each of said links at the raised portions of the links which result from the twisting thereof, and a bar-like calk secured at its ends to each of said links at depressed portions of the links, the calks of each link lying in crossed relation to one another.

In testimony whereof I, the said GILES A. BECKWITH have hereunto set my hand.

GILES A. BECKWITH.
